UNITED STATES PATENT OFFICE.

JOHN C. SCHELTER, OF ROCHESTER, NEW YORK.

LAST

Application filed October 28, 1924. Serial No. 746,422.

The present invention relates to lasts and more particularly to the type in which the fore part and the heel part are connected together by a bonding member which permits a relative movement between the parts for the expansion and the collapsing of the last. An object of this invention is to provide a construction in which the two locking devices provide a restricted space between them through which the bonding member moves upon the collapsing and the expansion of the last. A further object of the invention is to provide a last in which a locking device is arranged to cooperate with the side of the bonding member to hold the latter in expanded condition. Still another object of the invention is to provide a construction in which the bonding member is rigid and not elastic or resilient in the direction of its length, but is resilient in a direction transversely of its length, and a locking device cooperates therewith to hold the last in extended condition.

To these and other ends, the invention consists of certain parts and combinations of parts, all of which will be hereinafter described; the novel features being pointed out in the appended claims.

In the drawings:

Fig. 1 is a longitudinal section through a last constructed in accordance with this invention;

Fig. 2 is a similar view showing the last collapsed;

Fig. 3 is a section on the line 3—3, Fig. 1;

Fig. 4 is a fragmentary view of the rear end of the fore part of the last, showing the position of the bonding member when the last is locked in expanded condition;

Fig. 5 is a view similar to Fig. 4 showing parts in the position they occupy when the last is collapsed;

Fig. 6 is a longitudinal section of another embodiment of the invention showing the last expanded;

Fig. 7 is a longitudinal section of the embodiment shown in Fig. 6, showing the last collapsed;

Fig. 8 is a section on the line 8—8, Fig. 6;

Fig. 9 is an end view of the last shown in Fig. 6, showing the parts in the positions they occupy when the last is expanded; and

Fig. 10 is a view similar to Fig. 9, showing the parts in the positions they occupy when the last is collapsed.

Referring first to the embodiment of the invention shown in Figs. 1 to 5, inclusive, 1 indicates the fore part and 2 the heel part. These two parts are connected together by a bonding means, in this instance, in the form of a split tube or link 3 pivoted on a pin 4 extending transversely of the fore part and upon a pin 5 extending transversely of the heel part, the opposed faces of the fore part and heel part having respectively pockets 6 and 7 for receiving the pin. In order to remove the strain from the bonding means, the fore part and heel part have cooperating bearing surfaces. In this instance, a convex cylindrical bearing surface 8 is provided on the fore part, this surface being struck about a center X which when the last is expanded lies in a line above a line Y—Y, intersecting the centers of the pivots 4 and 5, and which when the last is collapsed lies below said line. The heel part of the last has a concave cylindrical surface 9 which conforms to the surface 8 and also has for its center the point X, when the last is expanded. Owing to the fact that the bonding member 3 turns about a center different from the center X, the heel part will when in collapsed condition be loose, so that it will move freely, but in expanded condition the surface 9 will be drawn into binding engagement with the surface 8, and strains removed from the pins 4 and 5 of the bonding member.

With the end in view of locking the last yieldingly in an expanded condition and preferably also in a collapsed condition, two locking devices 10 are provided, in this instance, in the form of short pieces of rod secured in small bores 11 on opposite sides of the pocket 6. These locking devices both extend into the path of movement of the bonding member and provide between them a restricted space through which the bonding member moves upon the expansion and the collapsing of the last, the bonding member, in this instance, due to its resilient construction, being distorted or compressed between the two locking devices so as to permit the movement of the bonding member through the restricted space. The cross sectional area of the bonding member is elliptical and as a consequence after the bonding member is forced between the locking devices upon the expansion or the collapsing movement of the last, the locking devices engage the convex upper or lower surface of the bond-

ing member and hold the last in an expanded or a collapsed condition.

In the embodiment of the invention shown in Figs 6 to 10, inclusive, those parts which are like the parts illustrated in Fig. 1 to Fig. 5, inclusive, are given the same reference characters. The differences in the two constructions reside in the bonding member and the locking devices. The bonding member 10^{3a} in this latter embodiment is in the form of a tube elliptical in cross-section, which is not split and does not have any material resiliency. It is also non-resilient or non-yielding in the direction of its length. The locking devices 10^a form a restricted space between them and are in the form of short split resilient tubes lying in the pockets 11^a. It is apparent that with this construction instead of the bonding member yielding to 20 permit the bonding member to pass through the restricted space between the two locking devices, the locking devices themselves yield to permit such movement and spring back over the bonding member to cooperate with 25 the convex upper and lower surfaces of the bonding member.

What I claim as my invention and desire to secure by Letters Patent is:

1. A last comprising a fore part, a heel part, a bonding member connecting said parts to permit their relative movement, and locking means for holding the last in an expanded and a collapsed condition, said locking means embodying two members providing a restricted passageway between them through which the bonding member is forced in moving from collapsed to expanded condition and vice versa, each of said members being arranged to engage the bonding member at two points, one for holding the last in an expanded condition and the other for holding the last in a collapsed condition.

2. A last comprising a fore-part, a heel part, a bonding member pivoted to the fore-part and also pivoted to the heel part, and a locking device for cooperating with said bonding member at two points between the two pivots and on opposite sides of a line through both pivots for holding the last collapsed or expanded.

3. A last comprising a fore-part, a heel part, a bonding member having a substantially elliptical cross section pivoted to the heel part and to the fore part, and a locking device cooperating with one side of the bonding member at two points between the two pivots of the latter and on opposite sides of a line through both pivots of the bonding member so that the bonding member moves past the locking device when the last is collapsed or expanded and the locking devices hold the last in a collapsed or an expanded condition.

4. A last comprising a fore-part, a heel part, cooperating bearings between said parts

permitting the relative swinging of the parts, a link pivotally connected to both parts, and a locking device to one side of the axis of swinging of the last parts cooperating with said link between the two pivots at 70 two points on opposite sides of a line through both pivots of the bonding member to hold the last in an expanded or a collapsed condition.

5. A last comprising a fore-part, a heel 75 part, cooperating bearings carried by the fore-part and the heel part, permitting the relative swinging of said parts, a tubular member having resilient walls and pivotally connected to both parts, and a locking device 80 cooperating with said link between the two pivots to hold the last in expanded condition.

6. A last comprising a fore part, a heel part, a bonding member connecting said parts to permit their relative movement, said bonding member being resilient in a direction transversely of the longitudinal axis of the last, and a rigid locking device past which the bonding member moves when the last is collapsed or expanded to cause the 90 bonding member to yield transversely.

7. A last comprising a fore part, a heel part, a bonding member connecting said parts and rigid in the direction of its length 95 but resilient in a direction transversely of its length, and two rigid locking devices providing a restricted passageway between them through which the bonding member is forced in moving to collapsed or expanded positions to cause the bonding member to yield transversely.

8. A last comprising a fore part, a heel part, a bonding member connecting said parts to permit relative movement between them, said bonding member being in the 105 form of a split resilient tube, and a rigid locking device past which the bonding member moves when the last is expanded or collapsed to cause the tube to yield transversely.

9. A last comprising a fore part, a heel 110 part, a bonding member in the form of a split resilient tube for connecting said parts and two rigid locking devices providing a restricted passageway between them through which the bonding member moves when the last is collapsed or expanded to cause the split tube to yield transversely.

10. A last comprising a fore part formed with a convex bearing surface at its rear end, a heel part formed with a concave bearing surface at its forward end for cooperating with the convex bearing surface on the fore part, and a bonding member secured to the heel part and pivotally connected to the fore part, said bonding member being rigid in the direction of its length and yielding in a direction transversely of the longitudinal axis of the last, and a rigid locking device on the fore part eccentric to the swinging axis between the last parts for 130

cooperating with the side of the bonding member as the latter moves on the pivot on the fore part to cause the bonding member to yield transversely.

5 11. A last comprising a fore part formed with a convex bearing surface at its rear end, a heel part formed with a concave bearing surface at its forward end for cooperating with the convex bearing surface on the fore part, and a bonding member secured to the heel part and pivotally connected to the fore part, said bonding member being rigid in the direction of its length and yielding in a direction transversely of the longitudinal axis of the last, and two rigid locking devices carried by the fore part and forming a restricted passageway between them through which the bonding member moves upon the collapsing and expansion of the last to cause the bonding member to yield transversely.

12. A last comprising a fore part formed with a convex bearing surface at its rear end, a heel part formed with a concave bearing surface at its forward end for cooperating with the convex bearing surface on the fore part, and a bonding member secured to the heel part and pivotally connected to the fore part, and two locking devices carried by the fore part at a point eccentric to the axis of turning between the fore part and the heel part and forming a restricted passageway between them through which the bonding member passes in moving from collapsed to expanded position, and vice versa, said locking devices each engaging the bonding member at two points, one to lock the last in collapsed condition and the other to lock the last in expanded condition.

40 13. A last comprising a fore part having its rear end provided with a cylindrical convex surface, a heel part having its forward end provided with a cylindrical concave sur-

face for cooperating with the convex surface of the fore part, a bonding member pivotally connected to the fore part and to the heel part and having its pivots when the last is expanded lying in a line which is below the center of the arc formed by the cooperating cylindrical bearing surfaces on the fore part and the heel part and when the last is collapsed lying above said center, and two locking devices carried by the fore part arranged eccentrically to the axis of turning between the fore part and the heel part and forming a restricted passageway between them through which the bonding member moves upon the collapsing and the expansion of the last, each of said locking devices engaging the bonding member at two points one to hold the last in an expanded condition and the other to hold the last in a collapsed condition.

14. A last comprising a fore part having its rear end provided with a cylindrical convex surface, a heel part having its forward end provided with a cylindrical concave surface for cooperating with the convex surface of the fore part, a bonding member pivotally connected to the fore part and to the heel part and having its pivots when the last is expanded lying in a line which is below the center of the circle formed by the cooperating cylindrical bearing surfaces on the fore part and the heel part, and when the last is collapsed lying above said center, said bonding member being rigid in the direction of its length and yieldable transversely of its length, and a rigid locking device carried by the fore part at a point eccentric to the axis of turning between the forepart and the heel part and past which the bonding member moves upon the collapsing and the expansion of the last.

JOHN C. SCHELTER.
